(57) **CLAIM**

The ornamental design for a filling nozzle as shown and described.

DESCRIPTION

FIG. 1 is a front elevational view of the filling nozzle of the present invention showing my new design, the rear elevational view being a mirror image of the front elevational view, and the top and bottom views each being identical to the front elevational view;

FIG. 2 is a right-side view thereof;

FIG. 3 is a left-side view thereof;

FIG. 4 is a top left perspective view thereof; and,

FIG. 5 is a top right perspective view thereof.

The broken lines shown in FIGS. 2, 3 and 4 represent portions of a filling nozzle and form no part of the claimed design.
